BRUSH

Walford A. Schwab, Chicago, Ill.

Application February 25, 1933, Serial No. 658,613

8 Claims. (Cl. 15—186)

This invention relates to improvements in brushes and, particularly, to brushes adapted to stimulate the growth of hair, eyebrows and eyelashes. The brush is designed to develop a healthy condition in the hair follicles and the scalp on which it is used by utilizing certain heretofore unappreciated physiological facts.

The invention will be readily understood from the following description in conjunction with the accompanying drawing, in which—

Figure 1 is a plan view of a brush embodying the invention; Fig. 2, an enlarged fragmentary sectional view taken along line 2 of Fig. 1; Fig. 3, an enlarged sectional view of a bristle embodying a modified form of the invention; Fig. 4, an enlarged sectional view of a bristle embodying a further modification; Fig. 5, an enlarged broken sectional view of the bristle shown in Fig. 2 in contact with a scalp; and Fig. 6, an enlarged broken sectional view of the bristle shown in Fig. 3 in contact with a scalp.

Referring to the drawing, 10 designates a hair brush of conventional design, including a handle 11 and a back 12. In the preferred embodiment 25 of the invention illustrated in Figs. 2 and 5, stiff bristles 13, comprising a stem or center portion 14 of steel, a phenolic condensation product or the like, and a rubber coating 15 are mounted preferably in staggered arrangement and relatively close together in a base 16 of flexible material, such as rubber, suitably secured to the back 12. The bristles may be secured to the base in any well-known manner. In Fig. 2 they are shown equipped with heads 13^a adapted to secure 30 them in the base, it being understood that the stem of the bristles is inserted in the base before the base is secured to the back. The tips 13^b of the bristles are carefully rounded and polished and protrude from the sheath or covering 15. The sheath is preferably molded of soft rubber, felt or a composition and encases the stem of the bristles in such manner that preferably only $\frac{1}{32}$ or $\frac{3}{64}$ of an inch of the tip of the stem is exposed.

The base 16 and the sheath 15 preferably comprise a unitary structure. In practice, the stems of the bristles are inserted in a die provided with elongated cylindrical forms terminating in a hole 50 to receive the tip of the stem and to self-center the stem. Suitable vulcanizable rubber is inserted in the forms and in a thin layer along the top of the die in such manner that only the heads of the stems protrude. The assembly is then introduced into a mold and vulcanized, thus pro-

ducing a molded unitary sheath enclosing the stem and a base of soft, flexible rubber.

In the modification illustrated in Figs. 3 and 6, the bristles 17 have a center portion 17^a of thin flexible steel wire terminating in a knob 17^b at their tips and a rubber covering 19. The bristles in this embodiment are mounted in a stiff base 18 of hard rubber or composition material. As shown in Fig. 3, the bristles are mounted in the base before it is secured to the back and the bristles are retained therein by their bent end-portions 17^c. All of the center portion 17^a of the bristles, except the knob 17^b, are enclosed in the soft rubber sheath 19, the knob or bulb alone protruding therefrom. The sheath or covering 19 is preferably molded on the bristles separately and suitably secured to the base by cement or glue, since the base is preferably molded from hard rubber or a composition and the sheath 19, from soft rubber.

A further modification is shown in Fig. 4. This embodiment is similar to that shown in Fig. 2 and comprises stiff bristles 20 having a center portion 20^a equipped with smooth rounded tips 20^b and a rubber sheath 21. The bristles are 25 preferably mounted in staggered arrangement in a flexible base 22. In this embodiment, the sheath encloses the entire center portion 20^a of the bristle and extends slightly beyond the tip 20^b.

As previously set out, the brush is adapted to 30 develop and maintain healthy scalp condition, not only on the surface but in the hair follicles. This desirable result is partially achieved by gently pulling the hair. The brush in its various forms has been designed to lightly pull the hair and it has been found that in practice it effectively achieves that result. In heads having a 35 normal growth of hair, the staggered arrangement of the bristles, their close proximity and the natural friction of hair and rubber tend to slightly tug the hair. The brush is most effective on scalps having a subnormal amount of hair. When the brush is drawn across the scalp, the bristles, in the preferred embodiment shown 40 in Fig. 2, assume approximately the angle shown in Fig. 5. The corners of the rubber sheath momentarily pinch the fine hairs against the scalp and tug them gently as the brush is moved. The slight pull of the hair tends to reduce the pressure within the hair follicle, causing blood and lymph to flow in and consequent stimulation of hair growth. The gentle tugging of the hair also produces a nervous stimulation, with a beneficial result. In the same stroke of the brush, the 45

tip of the bristle loosens and removes dandruff scales, desquamated epithelium and inspissated sebum from afflicted scalps. Vigorous brushing causes a slight movement of the entire scalp and effective massaging of the oil glands.

The action of the brush shown in Fig. 3 is substantially the same, except that the bristle itself bends, bringing both the sheath and the knob into contact with the scalp (Fig. 6) and 10 with the same highly desirable results.

It is to be understood that the use of a brush of this type is not limited to brushing hair; a smaller brush embodying my improved bristle and base may be employed in stimulating the 15 growth of eyebrows and eyelashes.

The foregoing detailed description has been given for clearness of understanding only, and no unnecessary limitations should be understood therefrom, but the appended claims should be 20 construed as broadly as permissible, in view of the prior art.

What I regard as new, and desire to secure by Letters Patent, is:

1. As a new article of manufacture, a brush 25 adapted to stimulate the growth of hair by securing maximum pull on the hair in brushing having bristles comprising metallic stems and a rubber sheath, said sheath including a covering for said stems and a base providing a mounting 30 for said stems.

2. A construction as called for in claim 1, in which the external tips of the stems protrude from the sheath.

3. As a new article of manufacture, a brush 35 adapted to stimulate the growth of hair comprising a back, bristles having metallic stems and a rubber sheath in the form of a unitary structure comprising a covering for said stems and a

base providing a mounting for said stems, said base being secured to the back.

4. A brush adapted to stimulate growth of hair, comprising a resilient base, stiff bristles mounted in said base in staggered arrangement 5 and a sheath of soft rubber enclosing all but the tips of said bristles, said sheath being adapted to pull hair in the brushing operation.

5. In a hair brush adapted to obtain the maximum pull on the hair in brushing, a base of flexible material, bristles mounted in said base, said bristles comprising stiff center portions, and a rubber covering enclosing all but the tips of said center portions.

6. In a hair brush, a rigid base, bristles mounted in said base, said bristles comprising a flexible center portion having a knob at its end and a rubber covering enclosing all but the knob of said center portions, said bristles being adapted to bend when brought into contact with a scalp 20 bringing said knobs and the ends of the rubber covering into contact with the scalp.

7. In a hair brush, bristles comprising a stiff metallic stem having a rounded tip and a soft rubber sheath enclosing all but the tip of said stem, and a base, said bristles being flexibly mounted in said base whereby the tip and the end of the sheath may be brought into contact with a surface to be brushed.

8. A hair brush adapted to stimulate the growth of hair by securing the maximum pull on hair in brushing, comprising a base and bristles mounted in said base, said bristles comprising a stiff longitudinal center portion and a covering of material having a coefficient of friction for hair substantially equivalent to that of soft rubber.
